190,300

COMBINED WIRE TENSIONER AND PULLER

Gerald A. M. Petersen, 460 Kifer Road, Santa Clara,
Calif., and Robert W. Goode, Morgan Hill, Calif.;
said Goode assignor to said Petersen

Filed Sept. 3, 1957, Ser. No. 47,589

Term of patent 14 years

(Cl. D41—1)

FIG. 1.

FIG. 2

FIG. 4

FIG. 3.

Fig. 1 is a top plan view of a combined wire tensioner and puller embodying our new design;

Fig. 2 is a side elevational view thereof, the side opposite that shown being substantially the same;

Fig. 3 is an end elevation thereof taken from the left of Fig. 2;

Fig. 4 is an end elevation thereof taken from the right of Fig. 2.

We claim:

The ornamental design for a combined wire tensioner and puller, as shown and described.
